(57) **CLAIM**

The ornamental design for a volatile liquid refueling probe, as shown and described.

DESCRIPTION

FIG. 1 is a top plan view of an ornamental design for a volatile liquid refueling probe of the present invention; FIG. 2 is a front view of an ornamental design for a volatile liquid refueling probe of the present invention; FIG. 3 is a left side view of an ornamental design for a volatile liquid refueling probe of the present invention; FIG. 4 is a rear view of an ornamental design for a volatile liquid refueling probe of the present invention; FIG. 5 is a right side view of an ornamental design for a volatile liquid refueling probe of the present invention; FIG. 6 is a bottom plan view of an ornamental design for a volatile liquid refueling probe of the present invention; FIG. 7 is an upper front end isometric view of an ornamental design for a volatile liquid refueling probe of the present invention; and, FIG. 8 is a lower rear end isometric view of an ornamental design for a volatile liquid refueling probe of the present invention. The broken lines shown in the figure are included for the purpose of illustrating portions of the volatile liquid refueling probe that form no part of the claimed design.
